UNITED STATES PATENT OFFICE.

ROBERT E. H. WURDISCH, OF SAN FRANCISCO, CALIFORNIA.

DUMP-WAGON.

No. 797,164.

Specification of Letters Patent.

Patented Aug. 15, 1905.

Application filed February 27, 1905. Serial No. 247,471.

To all whom it may concern:

Be it known that I, ROBERT E. H. WURDISCH, a citizen of the United States, residing in the city and county of San Francisco and State of California, have invented new and useful Improvements in Dump-Wagons, of which the following is a specification.

My invention relates to a wheeled vehicle having a body adapted to carry loose material and connections by which said body may be so disposed as to discharge its load and to again be returned to its normal position.

My invention comprises a combination of mechanism whereby the vehicle-body is raised into an inclined position, moved into a position to tilt and discharge its load, and return it again to its normal position.

It also comprises details of construction which will be more fully explained by reference to the accompanying drawings, in which—

Figure 1 is a side elevation with body in normal position. Fig. 2 shows body tilted. Fig. 3 is a partial section of gate and latch. Fig. 4 is a bottom view of same. Fig. 5 is a side view of front of body raised. Fig. 6 is a vertical section of same. Fig. 7 is a perspective view of winding-drum and clutch-sleeve. Fig. 8 is a plan view of same. Fig. 9 is a modification of tail-gate mechanism.

It is the object of my invention to provide a wagon or vehicle having a permanent bed and running-gear, with a body adapted to carry coal, ore, or any material which it is desirable to discharge from the body without handling, and in combination with said vehicle parts of mechanism by which the body may be raised into an inclined position, allowed to run backwardly by gravitation and to tilt and discharge its load, and then to be returned to its normal position ready for another load.

As shown in the drawings, A represents a bed-frame or running-gear of any suitable or desired description. When used for a road-vehicle, it will be mounted upon wheels B, with the usual connections for a team by which the wagon may be hauled from place to place. If adapted to a mining-car, the construction of the bed or wheels will conform to the tracks or whatever support the car may be designed to run upon.

Hinged to the rear portion of the frame A is a frame 2, which may be raised or depressed about its hinge-point. In its normal position it stands substantially parallel with the frame A and between the side timbers of this frame.

The front end of this frame 2 is adapted to be raised by mechanism to be hereinafter described, so as to stand at a considerable angle, and the wagon-body 3 is so mounted upon this frame that when the frame is raised into the inclined position the wagon-body may slide backwardly upon the frame.

4 represents rollers loosely journaled upon a shaft carried upon the rear axle-bed, and the longitudinal timbers of the body 3 are adapted to travel upon these rollers, so that the body may be slid backward and forward with least friction. At the front end of the body are other rollers journaled, as at 5, so as to rest upon the frame-timbers 2, and the plates in which the rollers are journaled may be extended downwardly upon each side of the timbers, as at 5^a, so as to prevent side motion of the body or the displacement of the rollers from the timbers on which they travel. The rollers 4 being flanged will perform a like office for the rear end of the body, and in addition to this I have shown hook members 6 extending upwardly upon each side of the bottom timbers of the body 3 and contiguous to the rollers 4.

Upon the side of the bed-timbers A are fixed vertically-slotted plates, as at 7, and upon the sides of the bottom timbers of the body 3 are fixed pins, as at 8, which project so that when in line above the slots in the plate 7, the body being then in an inclined position, the body may be let down by the actuating mechanism and the pins will enter the slots in the plates, thus locking the body and preventing its running backward or forward. When the body is allowed to move backwardly to the point where it will tilt and discharge its load, the pins 8 will contact with and be arrested by the hooks 6, thus preventing the body from traveling any farther to the rear, and in this position the body may tilt to such an angle as to discharge its load by gravitation. The incline of the timbers 2 when raised into position for the body to run back and discharge is sufficient to lift the pins 8 out of the slots in the plates 7 and above the rear side of the slots, so that when the body is released these pins will pass over the rear sides of the slots as the body moves backwardly. When the body is again drawn to the front by the actuating mechanism, the pins 8 will pass over the rear sides of the slots and will contact with the front sides of the slots in the plates 7, these sides being extended enough higher than the rear sides to form stops and

prevent any further forward movement of the pins or the wagon-body.

The rear gate 9 has hinges or pivots by which its upper edge is turnably connected with the top of the body 3. Projecting downwardly from the lower edge of this tail-gate are stout bars 10, and these bars when the gate is closed fit into slots 11, made in the rear part of the bottom of the vehicle, the bars projecting slightly below the bottom. Pivoted beneath the bottom are latches 12. The inner ends of these latches are each bent inwardly at an angle, as shown, and are pressed upon by springs 13, so that when free the outer ends of the latches will hook over and engage with the lower ends of the bars 10, thus holding the tail-gate in a locked position.

The releasing mechanism consists of a slideable bar 14, moving in guides and having rollers or other antifrictional contacting-surfaces at the ends, which when the bar is drawn forward will press against the angular portions of the hook-levers and pressing them both out of their normal position against the tension of the springs 13 will disengage the hooks 12 from the bolts 10, thus releasing the tail-gate. The bar 14 is connected by links, as at 15, with a rocker-arm 16, connected with the shaft 16, which is journaled across the lower part of the wagon-body, as shown. A lever 18 is fixed to the outer end of this shaft, projecting up along the side of the body of the vehicle and is connected by a rod 19 with the hand-lever 20, pivoted upon the side of the wagon-body and extending up to within easy reach of the driver. A suitable curved rack 21 serves to hold the lever in any desired position.

Extending rearwardly from the upper end of the rocker-arm 18 is a link 22, having its rear end connected with pins projecting from the side of the tail-board 9, and its front end has a slot made in it, as shown at 23. Within this slot the upper end of the rocker-arm 18 will move during the first portion of the movement of the lever 20 and of the rocker-arm 18. This allows the rocker-arm 16 to act through the link 15 upon the slide 14 to first disengage the hooks 12 from the pins 10, thus releasing the gate. The further movement of the rocker-arm 18 brings its upper end into contact with the rear of the slot 23, and it then pushes upon the links 22, one on each side of the body, and turns the tail-gate about its hinge-rod at the top, so as to swing it upwardly and leave the rear end of the vehicle open and free.

The movement by which the frame 2 is raised from its normal position into an inclined position which will allow the body to run rearwardly is effected by means of drums 24. These drums are here shown as loosely turnable upon a central shaft extending beneath the vehicle-seat or at other convenient

point at the front, and upon the same shaft is an inner drum 25 also loosely turnable. The drums 24 have flexible bands or ropes adapted to coil upon them, and the ends of these bands are connected by links with the front end of the tiltable frame-timbers 2, so that when these drums are revolved to wind up the flexible bands the front ends of the timbers will be lifted until they are in the proper inclined position, and this will raise the pins 8 out of the channels in the slotted plates 7, so that the body is free to move backwardly, as previously described.

The inner drum 25 has wound upon it ropes or flexible connections, the ends of which are connected with the lower part of the body 3.

For convenience in operating these ropes may pass around guide-pulleys 26, and when the inner drum is released, the body being in the inclined position, the ropes will be free to turn to unwind from the drum and the body will run backwardly upon its inclined support until the pins 8 are stopped against the hooks 6 and the body is in position to tilt and discharge its load. In order to operate the outer drums 24 and the inner drums 25 independently of each other, I have shown a clutch 34, located between the outer and the inner drums. This clutch is here shown in the form of a sleeve 34, turnable with the shaft 34^a, and in the ends of the sleeve pawls 27 and 33 are pivoted so that they may be moved to engage with either the outer or the inner drums.

The pawls are here shown as pivoted upon the sleeve 34 and are acted upon by spring-pressed pins 28, slideable within the sleeve and acting normally to force the points of the pawl 27 into engagement with a corresponding notch on the end of the drum 25. In this condition the drums 24 may be revolved to raise the frame 2 by turning the shaft 34^a in one direction, and as it is desired to revolve the outer drums 24 first in order to raise the supporting-timbers 2 and the body to stand at the required angle to cause the body to move backwardly, the pawl 27 is disengaged from the central drum 25 by the pressure of a lever 29, which is fulcrumed in line with the slot in which the pawl 27 stands diagonally between the drum 24 and the sleeve 34, and when this lever is pressed down it enters the slot or channel and in this position stands in line, so that when the sleeve begins to turn the drums 24 the pawl will be forced back and out of engagement with the drum 25. The drum 25 will be held in place and prevented from turning by means of a band-brake 30, which is actuated by a foot-lever 31 within convenient reach of the driver. This foot-lever being pressed down brings such tension upon the band-brake as to prevent the central drum from revolving. The outer drums may then be revolved by means of a bevel-gear 32, fixed upon the outer end of the

shaft, and a clutch formed by a spring-pressed pawl 33, engaging the outer drum with the sleeve 34, which is fixed to the shaft between the drums 24 25.

A convenient connection for the driver is by means of a vertical turning shaft 35, with a handle or wheel upon the top and a pinion 36 engaging with the gear-wheel 32. Thus by turning this shaft, and through it the gears, the pawls 33 of the clutch member will engage the drums 24, and when the drums are turned round by the application of power the flexible bands connecting with the tiltable bars 2 will be coiled upon the drums and the front end of the bars 2 will be raised into the desired inclined position. Ratchet-and-pawl mechanism, as shown at 37, serve to hold these drums and retain the timbers 2 in their inclined position. The body 3 is then in readiness to run backwardly by gravitation whenever released. This release is effected by disengaging the band-brake by means of the foot-lever 31, and as the pawls and ratchets 37 prevent the drums 24 from revolving, while the central drum 25 is free to revolve, it will be manifest that the timbers 2 will be held in their inclined position, while the drum 25 revolves freely, allowing the ropes to unwind until the body has reached the position in which it will tilt, the gate having been opened previous to raising the front end of the body into its inclined position. The load having been thus discharged, the central drum may be wound up as follows: By turning the winding-shaft 35 in the opposite direction from the movement required to raise the body into its inclined position the clutch-pawls 33 will move freely past the notches in the drums 24, which they engage when moving in the opposite direction. The first revolution of the clutch-sleeve 34 will cause the pawl 27 to raise the lever 29 by reason of the rear portion of the pawl contacting with the lever as it passes beneath it, and the lever will thus be raised out of the way of the pawl. The spring by which the pawl is pressed will then force the pawl to engage with the drum 25, and the winding-up of the ropes which draw the body forward will thus be effected. The body will be first tilted forwardly upon the supporting drums or rollers 4, and when its front end rests upon the inclined timbers 2 the continued revolution of the drum 25 will wind the ropes up until the body has been brought forward, and the pins 8, contacting with the front sides of the slots in the plates 7, will arrest this forward movement. The foot-lever 31 being then pressed down, the band-brake which it actuates will firmly grip the drum 25 and prevent its again unwinding to allow the body to run backwardly. The pawls which engage the ratchets at 37 may be then lifted by means of a connecting rod or link 40, the lower end of which is connected with a rocker-arm mounted upon a shaft 39, and this rocker-

arm and one at the opposite end of the shaft act as lifters, so that when the link or rod is pulled upwardly the pawls will be disengaged, and the drums 24 will then be free to revolve and allow the timbers 2 and the body resting upon them to sink to their normal and approximately horizontal position. The rear gate being closed by movements opposite to those which opened it, the body will be in readiness to receive another load.

In Fig. 9 I have shown a means for moving the tail-board 9 forward as it opens, so as to insure a better clearance for the discharging load. In this construction the upper edge of the tail-board is pivoted to the end of levers 9^a, and these levers are fulcrumed, as at 9^b. The opposite ends of these levers are connected and movable with the links 22, which may be slotted for the purpose. The movement of levers 22 to push the tail-board up also swings the levers 9^a to simultaneously pull the tail-board forward as it tilts upward.

Having thus described my invention, what I claim, and desire to secure by Letters Patent, is—

1. In a dumping-wagon and in combination with the body and running-gear thereof, a supplemental frame hinged at the rear having the front end free to move, a mechanism including winding-drums and flexible bands fixed thereto and connecting with the front of said frame, by which the front of said frame may be raised and depressed, and supports upon which the vehicle-body is slidable upon said frame.

2. In a dumping-wagon, a wheel-frame, a supplemental frame hinged at the rear thereof, mechanism including winding-drums and flexible bands fixed thereto and connecting with the front of said frame, by which the front of said frame may be raised into an inclined position, bearing-rollers journaled at the rear of the main frame, a body having the rear portion guided to travel upon said rollers, and guides and rollers at the front of said body, said rollers movable upon the tilting frame.

3. In a vehicle, a main frame having rollers at the rear, a supplemental frame having its rear end hinged to the main frame, mechanism including winding-drums and flexible bands fixed thereto and connecting with the front of said frame, by which the front of said supplemental frame may be raised to stand in an inclined position, a vehicle-bed with rollers at the front resting upon the supplemental frame, guides by which the body is maintained in its line of travel upon the frame and stops by which its rearward movement thereon is limited.

4. In a dumping-wagon, a main frame having rollers at the rear, a supplemental frame hinged at the rear, mechanism by which the front of said frame may be raised to stand at an incline, rollers and guides by which the ve-

hicle-body is movably supported upon the inclined frame, vertically-slotted plates fixed to the main vehicle-frame, and pins projecting from the sides of the vehicle-body engaging said slots to lock the body when the supplemental frame is down, said pins being disengaged to allow the body to move rearwardly when the inclined frame has been raised.

5. In a dumping-wagon, a main wheeled frame having rollers at the rear, a supplemental frame with mechanism by which it may be raised into an inclined position, a vehicle-body resting upon the rear rollers and having rollers at the front to travel upon the inclined frame, vertically-slotted locking devices upon each side of the main frame, pins fixed to the body engaging said slots when the body is in its normal position and disengaged therefrom when it is raised to an inclined position, and stops at the rear of the main frame against which the pins contact to limit the rearward motion of the body, said stops acting as guides to prevent said displacement of said body.

6. In a dumping-wagon, a main frame, a supplemental frame hinged at the rear, a body resting upon said frame antifrictional devices whereby the body is freely movable upon the frame, mechanism by which said frame may be raised into an inclined position, said mechanism consisting of winding-drums, flexible bands fixed to said drums and connecting with the front ends of the supplemental frame and a turnable shaft and mechanism intermediate between said shaft and the drums whereby the drums may be revolved.

7. In a dumping-wagon, a main wheel-frame, a supplemental frame hinged thereto at the rear, a body, rollers and guides whereby said body is movable in the direction of its length upon the supplemental frame, elevating mechanism consisting of winding-drums and flexible bands connecting said drums with the front ends of the supplemental frame, an intermediate independently-revolvable drum, cords connecting said drum with the vehicle-body, and means for controlling the revolutions of said drum after the body has been raised to stand at an incline whereby the body is allowed to move into a dumping position by gravitation.

8. In a dumping-wagon, a main wheel-frame, a supplemental frame hinged thereto at the rear, a vehicle-body slidably guided upon the main and supplemental frame, drums with flexible bands connected with the front end of the supplemental frame, a turning mechanism for said drums whereby the frame may be raised into an inclined position, pawls by which the drums are locked and the position of the inclined drum maintained, an intermediate drum, cords connecting said drum with the vehicle-body, a brake by which said drum is prevented from revolving while the supplemental frame is being raised, said brake

when released allowing the body to move into a dumping position by gravitation and controlling its movements.

9. In a dumping-wagon, a main wheel-frame, a supplemental frame hinged at the rear, a vehicle-body, rollers upon which the body is freely movable in the direction of its length, winding-drums having flexible bands connecting with the front of the supplemental frame whereby said frame may be raised to an inclined position, an intermediate drum with cords connecting it with the vehicle-body, said drums being mounted upon a single shaft, clutches fixed to said shaft located between the frame and body controlling drums, said clutches being engaged to turn the frame-elevating drums, means by which the clutches are disengaged from the intermediate drum to allow it to revolve and the body to move into dumping position by gravitation, means by which the said drum is engaged with the body-controlling drum whereby said body may be returned to its normal position, ratchets and pawls by which the drums of the supplemental frame are retained in position during the operation of dumping and returning the body, means for disengaging said pawls to allow the supplemental frame and body to be lowered into the normal position.

10. In a dumping-wagon, a wheel-frame having rollers at the rear, a supplemental frame hinged to the rear frame at the rear, a vehicle-body resting upon the rear rollers having rollers at the front resting upon the supplemental frame, guides by which the line of travel of the body is maintained, locking devices by which the body is retained in its normal position, stops by which its rearward movement is limited when in dumping position, drums having flexible bands connected with the front ends of the tilting frame, said drums being mounted upon a shaft at the front of the vehicle, an intermediate drum mounted upon the same shaft, cords connecting said drum with the vehicle-body, clutches fixed to the shaft engaging and turning the outer drum to raise the supplemental frame, means by which said clutches are prevented from engaging the central drum and a brake by which the movement of said drum is controlled to allow the vehicle-body to move by gravitation into the dumping position, means by which the clutches are caused to engage the central drum so that the turning of the shaft will revolve said drum and return the body to its normal position, pawl-and-ratchet mechanism by which the supplemental frame is retained in its inclined position during its operation, means for releasing said ratchets to allow the body and supplemental frame to be lowered to their normal positions, and slotted locking-plates upon the main frame, pins upon the vehicle-body engaging said plates to retain the body in place.

11. In a dumping-wagon, a main wheel-

frame, a supplemental frame hinged at the rear, a vehicle-body freely movable upon said frames, a winding-drum mechanism by which the supplemental frame is raised into an inclined position, means for allowing the body to move rearwardly on said frame to a dumping position and to return the body to its normal position, a tail-gate hinged to the upper part of the body, and a lever mechanism by

which said gate is opened to discharge the contents.

In testimony whereof I have hereunto set my hand in presence of two subscribing witnesses.

ROBERT E. H. WURDISCH.
